UNITED STATES PATENT OFFICE.

WILLIAM A. PARSONS, OF FORT ATKINSON, WISCONSIN.

CAP FOR SILOS.

Application filed July 2, 1927. Serial No. 203,052.

This invention relates to improvements in caps for silos and other buildings having similar requirements. The primary object of this invention is to provide a cap,—particularly a ventilating cap, adapted to cover an opening in the roof or top wall of a building in such a manner that the cap can be securely anchored in a position to close said opening in combination with means for securely holding the cap in a generally upright position when removed from the opening, whereby injuries such as might result from the cap falling from the roof or tipping over may be avoided.

Further objects of my invention are to provide a cap, such as a silo cap, adapted for use for silos and other purposes which will not only be removable to allow the silo to be filled, but which can be securely held to the top of the silo in either the normal silo closing position or in a lateral position at one side of the opening; also to provide a silo cap which will serve as a ventilator and light admitting cap and a weather-proof closure for the filling opening; also to provide a silo cap adapted to be applied to a central opening in the top of the silo or adjusted to a lateral position of security leaving the opening wholly unobstructed so that the silo can be filled from the top along the longitudinal center line, thereby compacting the central portion of the contents relatively to the side portions thereof whereby the central mass will be of great density.

In the drawings:

Figure 1 is a view of my improved ventilator cap as it appears when applied to the top of a silo, a fragment of the roof wall being shown and the position of the cap when removed from the opening being also indicated by dotted lines.

Figure 2 is a view of the cap as seen from the under side.

Figure 3 is a fragmentary view on an enlarged scale illustrating the locking toggle with the cap in normal position and with the cap in open position, dotted.

Figure 4 is a fragmentary view of the locking lever and associated parts.

Figure 5 is a fragmentary view in horizontal section drawn on line 5—5 of Figure 4.

Like parts are identified by the same reference characters throughout the several views.

In Figure 1 a fragment of a silo top wall or roof 10 is illustrated, the general form of which is that of a truncated cone with a cen-

tral aperture 11 through which the silo may be filled and ventilated. The margin of the roof wall about the opening 11 is covered by a ring 12 having an upstanding flange 13 over which a cap flange 14 may fit. This cap flange is secured to the conical base portion 15 of a ventilator cap from which rises the cylindrical ventilator column 17. A suitable roof 18 is supported from the column 17 by a set of posts 20 and is preferably spaced by the posts from the top of the column to allow for a circulation of air. The sloping sides of the base portion are preferably provided with wire glass windows 21 of sufficient strength and durability, whereby sufficient light is admitted to enable workmen to perform their duties within the silo.

The ring 12 is secured to the flat annular portion 22 of the roof 10 by bolts 23, and at one side of the opening 11 the ring flange 13 is provided with brackets 25 which are secured thereto by bolts or rivets 26. These brackets are spaced apart at a distance of about 90° within the circle occupied by the flange 13 and their inner sides are substantially parallel with each other. Link bars are pivotally secured to the brackets by pivot bolts 27 and connect them with depending brackets 28 attached to the cap flange 14. Each link bar has a downwardly inclined end portion 29 connected with the pivot bolt 27, the central portion 30 of the link bar being horizontally disposed and the opposite end portion 31 being upwardly inclined and connected with the bracket 28 by a pivot bolt 32. The object of inclining the end portions 29 and 31 is to enable the center portion 30 to be downwardly offset sufficiently to allow the link bars to swing to the inverted position in which they are indicated by dotted lines in Figure 1 when the cap is adjusted to open position as also indicated by dotted lines.

In the open position the offset portions of the link bars virtually form arches over the flange 13, the link bars being in effect arcuate bars. In the dotted line position the cap flange 14 rests upon the central portions 30 of the link bars and the ring finds a third point of support upon the roof as indicated at 35. Thereupon the inner margin of the cap may be so secured to the silo roof by any suitable connections such as a hook 37 engageable in an aperture 38 in the ring 14, said hook being connected with the silo roof.

In the construction shown an angle bracket 40 is secured to the ring flange 13 by bolts 41.

The horizontal inwardly projecting portion of this bracket receives a bolt 42, the lower end of which is reduced and threaded to receive the nut 43 underneath the bracket flange, whereas the upper or shank portion of the bolt has a shoulder engaging the upper surface of the flange to be clamped thereto by the nut 43. The shank portion of the bolt curves toward the central portion of the silo and is provided with one or more head pieces or ears 44 to which a toggle lever 45 is pivoted at 46. The pivoted end portion of this toggle lever is laterally offset at 47 and a link bar 48 is pivotally secured at 49. The other end of the link bar 48 is connected with the hook 37 by a coiled tension spring 50.

By swinging the operating lever 45 to the dotted line position in which it is illustrated in Figure 3 the hook 37 may be easily engaged with the ring 14, whereupon the lever 45 may be swung downwardly to the full line position in which it is illustrated in Figure 3. In moving to the full line position the pivot pin 49 swings across a line of centers between the pivot pin 46 and the point of engagement between the hook 37 and the ring 14. The spring 50 yields sufficiently to extend the linkage and allow said pivot pin 49 to follow the necessary arcuate path and after passing said line of centers the spring contracts slightly but retains sufficient tension to securely anchor the ventilator cap in the position in which it is indicated by dotted lines in Figure 1. The silo cap is thus supported upon the silo roof against wind pressures and also against any pressure that may be exerted thereon by workmen when filling the silo.

It will be observed in Figures 1 and 3 that the bolts 41 project for a short distance beyond the ring flange 13 thereby forming studs which engage in apertures 55 in the cap flange 14 when the cap is in its normal position for closing the opening 11. On the opposite side the cap flange 14 may then be secured to the flange 13 by a locking bolt or rod 56 of peculiar construction and function which will now be described.

The locking bolt 56 comprises the end portion of a rod which is bent to form a handle 57 the outer leg 58 of which is elbowed at 59, the end portion of the rod being extended through a notch 62 in the lower margin of the cap ring 14 (Figures 4 and 5) and through an aperture in the ring flange 13. The inwardly projecting end of the rod is provided with a suitable handle 65 and compression spring 66 is coiled about the rod and interposed between the cross pin 67 and the ring 13, whereby the rod is urged toward locking position with its locking bolt portion 56 engaged with registering apertures in the ring flanges 13 and 14 as best shown in Figure 1.

With the above described construction the silo cap may be unlocked either from the exterior or from the interior of the silo. When

it is to be unlocked from the exterior the operator will grasp the handle portion 58 and pull the rod outwardly until lock portion 56 is disengaged from said registering apertures in the rings. Thereupon the handle 58 may be swung to a horizontal position as illustrated in Figure 5 or by dotted lines in Figure 4. The portion 56 thereupon engages in the recess 62 at the enlarged end of said recess. The handle portion 58 may then be used as a lever to lift the ring 14 from the ring flange 13 on the side occupied by the lock. After slightly lifting the cap in this manner the ring 14 or any other portion of the cap may be grasped and additionally lifted until the cap has been raised far enough on this side to allow it to be shifted and disengaged on the other side from the stud bolt or bolts 41. Thereupon the entire cap may be additionally moved in the same direction until it reaches the Figure 1 dotted line position, the invertible link bars guiding it during this movement and limiting the movement of the cap so that it cannot tip over or fall from the roof. When adjusted to the open position it may be additionally secured by means of the hook 37.

It will, of course, be understood that when it is desired to release the cap from the interior of the silo the handle 65 will be employed to unlock the cap by retraction of the locking bolt 56.

It will be understood that my improved cap retaining and locking mechanism will be applicable to any form of roof cap or any cap subject to analogous use regardless of whether the same constitutes a ventilating cap or a cap provided with windows. Various structural modifications in the caps and in the locking mechanisms may be made within the scope of my invention and the words and terms employed in this description and in the appended claims are used for the purpose of description and not limitation.

I claim:

1. The combination with an apertured roof structure, of a cap adapted to normally cover the aperture in the roof, and a set of substantially parallel links connecting the cap with the marginal portions of the roof, said links being pivotally secured to the cap on the opposite side of a transverse diametrical center line from that at which the links are connected with the roof, and the central portions of the links being downwardly offset to allow a bodily shifting movement of the cap to one side of the aperture without inversion.

2. The combination with an apertured roof structure, of a movable cover cap linked to the roof structure within the aperture adapted to be bodily shifted to one side of the aperture without inversion, interlocking means for securing the cap in closing position, and co-operative toggle connections for securing the cap in the open position.

3. The combination with a roof structure

- provided with a circular opening, a ring secured to the roof structure about said opening and provided with an upwardly extending flange, a cap adapted to cover said opening and provided with a depending circular flange adapted to fit over the roof ring flange, brackets connected with the respective flanges on opposite sides of a diametrical center line, and parallel links connecting the roof ring brackets with the cap ring brackets, the central portions of said links being downwardly offset, whereby the links may swing to an inverted position over the roof ring when the cap is shifted to open position, and whereby said cap may be held without inversion upon the sloping portions of a roof.
4. The combination with a roof structure provided with a circular opening, a ring secured to the roof structure about said opening and provided with an upwardly extending flange, a cap adapted to cover said opening and provided with a depending circular flange adapted to fit over the roof ring flange, brackets connected with the respective flanges on opposite sides of a diametrical center line, and parallel links connecting the roof ring brackets with the cap ring brackets, the central portions of said links being downwardly offset, whereby the links may swing to an inverted position over the roof ring when the cap is shifted to open position, and whereby said cap may be held without inversion upon the sloping portions of a roof, said roof ring being also provided with a bracket between the link brackets, and toggle mechanism connected with the intermediate bracket and having means for interlocking engagement with the cap ring when the cap is in open position.
5. In a roof cap structure, the combination with a bracket adapted to be connected to the roof within a roof aperture normally covered with a cap, a lever pivotally supported from said bracket and having a portion projecting transversely of the pivotal axis in a position to swing across a vertical line through such axis, a link pivotally secured to the transversely extending portion of the lever, and a hook resiliently connected with said link and adapted for interlocking engagement with the cap.
6. The combination with an apertured roof structure having an upwardly extending flange along the margins of the aperture, a cap provided with a flange adapted to engage over the roof flange, linkage connecting the respective flanges and adapted to allow the cap to be shifted from a normal aperture closing position to a laterally offset position without disengagement from said linkage, means for normally interlocking the roof flange with the cap flange at one side of the aperture, and a spring actuated locking bolt adapted to connect such flanges at the other side of said aperture when the cap is in aperture covering position.
7. The combination with a roof structure provided with an aperture bordered by an upwardly projecting flange, of a ventilator cap having a depending flange adapted to cover the roof flange, linkage connecting the roof flange at one side of the aperture with the cap flange at the other side of the aperture and adapted to swing to an inverted position of extension over the roof flange for supporting the cap in a laterally offset position, and means for securing the cap in both the aperture covering position and in the offset position.
8. The combination with a roof structure provided with an aperture bordered by an upwardly projecting flange, of a ventilator cap having a depending flange adapted to cover the roof flange, linkage connecting the roof flange at one side of the aperture with the cap flange at the other side of the aperture and adapted to swing to an inverted position of extension over the roof flange for supporting the cap in a laterally offset position, and means for securing the cap in both the aperture covering position and in the offset position, said cap having a conically tapered base provided with windows and a central upwardly extending ventilator portion.

WILLIAM A. PARSONS.
